United States Patent Office

Des. 186,371
Patented Oct. 20, 1959

186,371

PANELLED BUILDING BLOCK

Arvid Johnson, Garden Grove, Calif.

Application October 14, 1957, Serial No. 48,077

Term of patent 14 years

(Cl. D18—2)

FIG. 1.

FIG. 2.

Figure 1 is a perspective view of a panelled building block, embodying my new design;

Figure 2 is another perspective view of the block, illustrating the rear thereof and the end not shown in Figure 1;

Figure 3 is a top plan view of the block, and

Figure 4 is a bottom plan view thereof.

I claim:

The ornamental design for a panelled building block, substantially as shown.
